UNITED STATES PATENT OFFICE.

HERMAN B. KIPPER, OF MUSKEGON, MICHIGAN.

PROCESS OF SPEEDING CHEMICAL REACTIONS.

Application filed May 14, 1926. Serial No. 109,149.

The present invention relates to the manufacture of sodium sulphate and hydrochloric acid from sulphuric acid and salt, or fused nitre cake and salt and has for its object to provide a process and apparatus whereby the speed of chemical reaction between sulphuric acid and salt or nitre cake and salt will be greatly increased to enhance the commercial value of the process and whereby caking of the material in the converter will be more effectively prevented than with the other hitherto known processes of the same kind.

To accomplish my object I utilize an apparatus constructed substantially as shown and described in my U. S. Letters Patent No. 1,512,226, but in which the scrapers, instead of revolving with the high speed of the grinding or beating hammers, are moved at a greatly reduced speed. I also provide a dam, which will hold back the reaction materials before they pass out from the converter as a result of which they are subjected to the action of the beating hammers for a longer period.

To make my invention more clear the apparatus used for carrying out the process is more or less diagrammatically illustrated in the accompanying drawing in which similar reference characters denote corresponding parts.

The well known reactions involved in this process are

The suitably preheated sulphuric acid and salt or ground or fused nitre cake and salt are fed into the reaction cylinder or converter 10 through a spiral conveyer *c* or other means. The cylinder 10 may be externally or internally heated in any suitable manner to a temperature of 200° to 800° C. In the reaction cylinder the said materials are subjected to the blows of rapidly revolving hammers 16 extending longitudinally through the apparatus and carried by rods 17 fixed to disks 18 substantially as described in my application Ser. No. 655,168 filed August 2, 1923. The disks 18 are mounted on and revolve with the shaft 14 that extends through the cylinder and is driven from a suitable source of power by pulley *P* and belt *B* or in any other suitable manner. As in said application the shaft 14 is hollow to form a passage for water or

other cooling medium and is externally isolated as at 15. In this construction the heads 11 of the cylinder 10 are fixed to the latter. Rotatively mounted on the shaft 14 near each end thereof are sleeves 19 with disks 20 to the periphery of which are fixed a plurality of bevelled bars 12 extending longitudinally of and close to the inner face of the cylinder. These bars 12 serve as scrapers and are adapted to prevent caking. A shaft 24 which is driven with greatly reduced speed from the shaft 14 by suitable means transmits motion by sprocket chains and gears 21, 23 and 22 to the sleeves 19 so that the scrapers 12 will revolve concentrically with the hammers 16 but with relatively low speed and thereby more effectively keep the cylinder wall free from incrustation. The scrapers have suitably attached to them at the rear of and near the exit *c*¹ of the cylinder a rim or flange 13 which serves as a dam adapted to retard the exit of the reaction material prior to their passing into the discharge *c*¹ of the cylinder. While the reaction materials are thus retarded by the slow moving dam, they are subjected to a final and effective beating action of the rapidly revolving metal hammers 16, whereby the conversion efficiency of the apparatus is greatly enhanced.

The material leaving the apparatus through the passage *c*¹ may if necessary be carried either through a dust or separation chamber 24 having a passage 24¹ or directly into a second converter (not shown) identically of the same construction as the one described, in which they are treated once more in the same manner.

In my experiments with the process I have used metal parts of different shapes but have described and shown only those most advantageous. I do not wish, however, to restrict myself to any of the details shown and described, since various modifications may be made without departing from the principle of my invention.

During the passage of the material through my converter I have spoken generally of its grinding action or effect. The term might be said to have been employed relatively. Thus mixing and grinding may merge into one another as day into night. If the raw materials are ground very fine, say to a 300 mesh size, they leave the converter somewhat coarser. On the other hand if they enter the converter say at a 20 mesh

size they leave it in a much finer state. Aggregation and grinding are both continually taking place. Again the speed at which the rapidly moving metal parts travel (I use generally from a half a mile to a mile a minute) largely determines the fineness of the finished product. The efficiency of the apparatus is increased with increase of speed of the rapidly moving parts within such limit as are mechanically practical.

10 What I claim is:

1. In the process of producing sodium sulphate and hydrochloric acid from sodium chloride and sulphuric acid or sodium hydrogen sulphate the steps of grinding and beating the reaction materials in a heated vessel by rapidly moving metal parts and keeping said vessel free from caking of the material by slowly moving metal parts.
- 15 2. In the process of producing sodium sulphate and hydrochloric acid from sodium acid and sodium hydrogen sulphate and of producing sodium hydrogen sulphate and hydrochloric acid from sodium chloride and sulphuric acid, the steps of grinding and beating the reaction materials in a heated vessel by rapidly moving metal parts and keeping said vessel free from caking by the materials therein contained by slowly moving metal parts.
- 20 3. In the process of producing sodium sulphate and hydrochloric acid from sodium acid and sodium hydrogen sulphate and of producing sodium hydrogen sulphate and hydrochloric acid from sodium chloride and sulphuric acid, the steps of grinding and beating the reaction materials in a heated vessel by rapidly moving metal parts and keeping said vessel free from caking by the materials therein contained by slowly moving metal parts.
- 25 4. In the process of producing sodium sulphate and hydrochloric acid from sodium acid and sodium hydrogen sulphate and of producing sodium hydrogen sulphate and hydrochloric acid from sodium chloride and sulphuric acid, the steps of grinding and beating the reaction materials in a vessel heated to from 200 to 800 degrees C. by rapidly moving metal parts, of keeping the vessel free from caking by the materials contained therein by slowly moving metal parts and retarding the too rapidly passing out of the finished products by a suitable dam, partially restricting the reaction vessel at the outlet end.
- 30

3. In the process of producing sodium sulphate and hydrochloric acid from sodium acid and sodium hydrogen sulphate and of producing sodium hydrogen sulphate and hydrochloric acid from sodium chloride and sulphuric acid, the steps of grinding and beating reaction materials by rapidly moving metals parts, of keeping the vessel free from caking by the materials therein contained by slowly moving metal parts and of retarding the too rapidly passing out of the finished product by a dam, partially restricting the reaction vessel at the outlet end.

4. In the process of producing sodium sulphate and hydrochloric acid from sodium acid and sodium hydrogen sulphate and of producing sodium hydrogen sulphate and hydrochloric acid from sodium chloride and sulphuric acid, the steps of grinding and beating the reaction materials in a vessel heated to from 200 to 800 degrees C. by rapidly moving metal parts, of keeping the vessel free from caking by the materials contained therein by slowly moving metal parts and retarding the too rapidly passing out of the finished products by a suitable dam, partially restricting the reaction vessel at the outlet end.

In testimony whereof I affix my signature.
HERMAN B. KIPPER.
